CLAIM

The ornamental design for a computer mouse, as shown and described.

DESCRIPTION

FIG. 1 is a perspective view of a computer mouse in accordance with the new design;

FIG. 2 is a front view of the computer mouse of FIG. 1;

FIG. 3 is a back view of the computer mouse of FIG. 1;

FIG. 4 is a left side view of the computer mouse of FIG. 1;

FIG. 5 is a right side view of the computer mouse of FIG. 1;

FIG. 6 is a top view of the computer mouse of FIG. 1;

FIG. 7 is a bottom view of the computer mouse of FIG. 1;

FIG. 8 is a perspective view of a second embodiment of the computer mouse in accordance with the new design;

FIG. 9 is a front view of the computer mouse of FIG. 8;

FIG. 10 is a back view of the computer mouse of FIG. 8;

FIG. 11 is a left side view of the computer mouse of FIG. 8;

FIG. 12 is a right side view of the computer mouse of FIG. 8;

FIG. 13 is a top view of the computer mouse of FIG. 8; and,

FIG. 14 is a bottom view of the computer mouse of FIG. 8.

Broken lines seen in the drawings depict portions of the computer mouse that form no part of the claimed design.

1 Claim, 10 Drawing Sheets
